DRAGLINE ROCK SCRAPER

Andrew O. Olson, Snohomish, Wash.

Application December 30, 1935, Serial No. 56,758

2 Claims. (Cl. 37—120)

This invention relates to improvements in rock handling scrapers, and it has reference more particularly to what may be termed drag line rock scrapers, and which are of a character designed particularly for use in placer mining operations, although not to be limited to such use.

It is the principal object of this invention to provide a drag line rock scraper particularly suited to placer mining operations in that it may be used after the fashion of the ordinary drag line bucket, and whereby the earth adjacent a cut that is being made in a sluicing operation may be dragged into the cut to permit the "pay dirt" to be washed out and whereby the heavy rock that is dragged in with the "pay dirt" and which is detrimental to the sluicing operation, may be removed.

Explanatory to the present invention, it will here be stated that in placer mining operations and in sluicing a cut, it is now the common practice to convey the earth from opposite sides thereof into the cut from which it is washed into the sluice box. This conveying of earth has been accomplished in various ways, both manually and mechanically. The difficulty heretofore encountered in the use of ordinary types of drag buckets resides in the fact that these buckets do not provide for segregating the heavy rock from the "pay dirt". For instance, when it is desired to remove rock from the cut with the bucket, the bucket also takes with it a certain amount of the "pay dirt". Also, when earth is dragged into the cut, there is no way of segregating the rock from the "pay dirt" and, as a consequence, the sluicing operations are greatly hindered for the reason that heavy rock in the cut retards the washing of the "pay dirt" into the sluice box.

In view of the above, it has been an object of the present invention to provide a novel form of drag line rock scraper that is formed by a plurality of spaced, parallel drag hooks having their shank portions rigidly joined together by a back plate, thus providing a form of drag line bucket wherein the back portion is closed by the plate while the base portion comprises only the spaced hooks between which the loose dirt and small rocks may readily pass, while the larger rocks may be retained therein for removal from the cut.

It is a still further object of the invention to provide a drag line rock scraper that may be manipulated in the same manner as the present day line bucket, and which may be drawn along the sluicing cut to pick up the large rocks which

interfere with the sluicing operation in the cut and which provides also that all "pay dirt" that is dragged into the cut by the scraper may easily and readily be washed out as the scraper is held suspended over the cut or over the sluicing box, and the larger rock will be retained and may be discharged onto a dump at some point remote from the cut.

Other objects of the invention reside in the details of construction and in the combination of parts, and in the novel method involved in the use of the device, as will hereinafter be described, and pointed out in the claims terminating the specification.

In accomplishing these and other objects of the invention, I have provided the improved details of construction, the preferred forms of which are illustrated in the accompanying drawings, wherein—

Fig. 1 is a side view of a rock scraper embodied by the present invention.

Fig. 2 is a side view showing the bucket in its suspended position and illustrating the operation of washing the dirt from the scraper while the heavy rocks are retained.

Fig. 3 is a top, or plan view of the device, as seen in Fig. 1.

Fig. 4 is a lower end view of the scraper.

Referring more in detail to the drawings—

The present rock scraper comprises a plurality of heavy, substantial hooks 1 arranged in spaced, parallel planes across the width of the scraper. All the hooks are transversely aligned and the shank portions 1a thereof, which are substantially straight, are rigidly joined by a back plate 2 that is secured to the shank in any suitable manner, such as by welding, and which plate serves to close the back side of the scraper bucket thus formed. The lower end portions 1b of the hooks form the bottom of the bucket and each hook is equipped with a digging tooth 3 secured in the hook end by suitable means. The hooks that are at the extreme opposite sides of the bucket have web plates 5 across the curved base portions, as shown in Figs. 1 and 4, thus to partially close the sides of the bucket.

Interposed between the end portions of the various hooks are spacers 6 of tubular character, and a continuous rod 7 is extended through the hooks and through the spacers, thereby to rigidly unite all of the hooks. The ends of the hooks, as will be noted in Fig. 1, extend forwardly, substantially parallel with the shank portions 1a, thus to insure retaining a substantial load when the bucket is lifted.

As a means of handling the scraper, it is equipped with a surrounding frame of channel iron. This comprises opposite side beams 8 and 8' and a base beam 9 across the bottom of the bucket permanently secured to the hooks. The forward, or upper ends of the beams 8-8' are united by fish plates 10 with the upper ends of the shanks of the hooks, and a cross beam 11 is disposed transversely across the shank ends of the hooks and this is rigidly secured to the frame structure at a medial point by the brace members 12 and at the ends by the brackets 13, as shown best in Figs. 1 and 4.

Drag chains 14 and 14' are secured to the forward or upper end of the bucket at opposite sides and are extended forwardly to a clevis 15. Also, there are supporting chains 16 and 16' attached to the opposite sides of the bucket by pivotal connection 17 with brackets 18, which, in turn, are secured to the beams 8 and 8'. The upper ends of the chains 16-16' connect with a pulley block 20 to which a hoist line 21 is pivotally attached. Also, a line 22 is secured to the clevis, and passes over the pulley block 20 and downwardly, and is pivotally attached, as at 25, to the transverse beam 11 at a medial point. A drag line 26 is attached to the clevis, and this line and the line 21 are extended to the power devices which operate the scraper.

Assuming that the scraper is so constructed, it is apparent that in the position of Fig. 1, it may be dragged along the ground; for instance, along the sluice channel, and when so drawn, the teeth will dig into the ground, and the bucket will be filled with the rock and dirt. In the usual operations, the bucket is lifted and held suspended over the channel that is being sluiced or over the sluice box, and water from a hydraulic nozzle 30 is discharged into the bucket as illustrated in Fig. 2. This washes all of the "pay dirt" from the scraper, but the scraper retains the heavy rocks, which are then conveyed out of the way and dumped from the scraper.

The mode of operating the bucket through the intermediary of cables 21 and 26 is well understood by those familiar with the handling of drag line buckets, and since this is not a part of the present invention per se, it will not be further described.

Scrapers of this character have proven to be an economical means of removing rock, particularly in mining operations. However, it is to be understood that it is not the intention that the scraper be confined in its use to mining operations. Such scrapers may be made in various sizes, and in various widths, and the hooks thereof may be located at such spacing as will best suit the particular purpose to which the bucket is to be put.

The particular advantage to be gained by this type of scraper is that the "pay dirt" may be easily and readily washed therefrom while all heavy rock is retained and may be removed thereby from the sluicing cut.

Having thus described my invention, what I claim as new therein and desire to secure by Letters Patent is—

1. A rock scraper of the character described, comprising a frame structure equipped for attachment to operating lines, a plurality of drag hooks fixed in the frame, transversely aligned and in spaced relation, and a cover plate, secured across the shank portions of the hooks and closing only the back portion of the bucket formed thereby and an operating line whereby the bucket may be held in suspended position.

2. A device as recited in claim 1, wherein the hook portions proper of the hooks are curved to dispose their end portions substantially parallel with the shank portions of the hooks, and wherein in the hooks at the outside have webs applied to the hooked bases to partially close the sides of the bucket formed by the hooks.
